Ex

OR D 15,040

No. 15,040 June 3, 1884

UNITED STATES PATENT OFFICE.

CHARLES W. NEWMAN, OF CHICAGO, ILLINOIS.

DESIGN FOR AN ORGAN-CASE.

SPECIFICATION forming part of Design No. 15,040, dated June 3, 1884.

Application filed March 27, 1884. Term of patent 3½ years.

To all whom it may concern:

Be it known that I, CHARLES W. NEWMAN, a citizen of the United States, residing at Chicago, in the county of Cook and State of Illinois, have invented and produced a new and original Design for Organ-Cases, of which the following is a specification, reference being had to the accompanying illustration, forming part thereof, and showing a perspective view of my newly-designed case.

A designates the main body of the upright organ-case, and *a* a suitable base-piece cut away, as shown, at its corners and front. The ends of the case are provided with the vertical ornamental posts or moldings *a'* *a''*, between which are the panels *b* and *b'* and the end strips, *b''*. The front corners of the case are beveled, and consist of the panels *B*, suitably ornamented, as shown. From the front posts, *A'*, of the case extend the ornamental brackets *C*, connected to the foot brackets *C'* by the posts *c*. The front of the lower portion of the case is furnished with the ornamental panels *d*, *d'*, and *d''*, separated by suitable moldings, as shown. The face of the keyboard consists of the scroll-work *E*, and above the stops is the ornamental scroll-work panel *F*, upon the sides of which are the side brackets, *e*, and the inclined panels *e'*. Upon the top of the case is placed the cover *A''*, from which rises the top board, *G*, ornamented by end brackets, *g*, posts *g'*, projections *g''*, posts *g'''*

and head-piece *g''*, with posts *g'''*. Extending from the central portion of the top board is the music-case *H*, having the ornamental face-panel, as shown; and above this case and supported upon brackets *h* is the small top shelf, *I*.

The several ornamental panels above described will be adapted to contrast with the color of the moldings.

What I claim as new and original, and desire to secure by Letters Patent, is—

1. The new and original design for an organ-case herein shown and described. 45
2. In a design for an organ-case, the end wall thereof consisting of the upright posts *a'* *a''*, panels *b* *b'*, and beveled corner-panel *B*, substantially as shown.
3. In a design for an organ-case, the top 50 thereof consisting of the ornamental board *G*, provided with curved projections and posts, as shown, and bracketed shelf *I*, substantially as shown.
4. In a design for an organ-case, the front 55 thereof consisting of the posts *A'*, ornamental brackets *C* *C'*, posts *c*, panels *d* *d'* *d''*, keyboard-face *E*, panel *F*, brackets *e*, panels *e'*, and cover *A''*, substantially as shown.

CHARLES W. NEWMAN.
